UNITED STATES PATENT OFFICE

2,324,692

LOAD COMPENSATED CONTROL SYSTEM

Willis H. Gille, St. Paul, Minn., and John V. Sigford, Wabash, Ind., assignors to Minneapolis-Honeywell Regulator Company, Minneapolis, Minn., a corporation of Delaware

Application April 14, 1941, Serial No. 388,368

8 Claims. (Cl. 236—74)

This invention relates to proportioning control systems in general, and has for an object to improve that type of proportioning control system wherein means is provided to change the setting of the system in response to a change in the system load.

Another object of the invention is to provide a load compensating mechanism for a follow-up control system in which the condition responsive element is a variable resistance.

A further object of the invention is to provide, in a follow-up control system for controlling a condition in response to the unbalance of a Wheatstone bridge circuit, means for compensating the control effect of a given condition value in accordance with the load on the system. A still further object of the invention is to provide, in a system of the type described, means for changing the condition value maintained by the control system.

Other objects and advantages will become apparent to those skilled in the art upon reference to the accompanying specification, claims and drawing, in which:

The single figure diagrammatically discloses a follow-up control system embodying the load compensating mechanism of our invention. Certain features essential to our invention are shown on an enlarged scale, while other features of conventional construction are reduced.

The drawing shows a furnace 10 having a burner 11 which is supplied with fuel through a conduit 12 controlled by a valve 13. Heated fluid is carried from the furnace 10 through a pipe 14 to a heating system including a radiator 15. In the radiator 15 the fluid gives up its heat to the space in which the radiator is located and the spent fluid then returns to the furnace 10 through a pipe 16.

The valve 13 is operated by a stem 20 on which is mounted a rack 21. The rack 21 is driven by a pinion 22 operated by a motor generally indicated at 23 through a gear train schematically shown at 24. The motor 23 has a pair of windings 25 and 26 which operate the motor in opposite directions.

Energization of the windings 25 and 26 is controlled by a switch arm 30 moving between opposed stationary contacts 31 and 32. The switch arm 30 is mounted on the moving coil 33 of a galvanometer generally indicated at 34. The galvanometer 34 is connected to a bridge circuit 40 having input terminals 41 and 42 and output terminals 43 and 44. Three of the arms of the bridge circuit consist of fixed resistances 45, 46

and 47. Between the arms 45 and 46 of the bridge is connected a slide wire resistance 50 across which a sliding contact 51 is moved. The sliding contact 51 is shown as rigidly attached to the stem 20 of the valve 13 for movement therewith. It should be noted that output terminal 44 of the bridge is the point at which contact 51 engages the resistance 50. The fourth arm of the bridge includes a temperature responsive resistance 52 located in the space heated by the radiator 15, and two rheostats 53 and 54.

The portion of the resistance 54 which is connected in series with the temperature responsive resistance 52 is controlled by a movable switch arm 55 driven by a reversible motor generally indicated at 56 through a gear train schematically shown at 57. The motor 56 is provided with a pair of windings 60 and 61 which operate the motor in opposite directions. The energization of these windings is controlled by a switch arm 62 which moves between opposed stationary contacts 63 and 64. The switch arm 62 is mounted on and operated by a temperature sensitive bimetallic element 65 which is exposed to the temperature of the space being heated by the radiator 15.

The bimetallic element 65 is fixed at the end opposite the contact arm 62 to a plate member 66 which is pivotally mounted as at 67 on a panel 68 in the space heated by the radiator 15. The temperature responsive resistance element 52 and the rheostat 53 are also mounted on the panel 68. A lever 70 is pivotally mounted as at 71 on the panel 68 and has a portion 72 projecting below the lower edge of the panel 68. An indicator pointer 73 is attached to the portion 72 of the lever 70 and cooperates with a scale 74 on the panel 68 to indicate the temperature which the system is set to maintain. An arm 75 is fixed to the lever 70 in any suitable manner and serves to vary the portion of rheostat 53 which is connected in series with the temperature responsive resistance 52, in accordance with the temperature setting of the system as determined by the position of the lever 70. The lever 70 also has an arm 76 extending toward the plate member 66 and having a suitable connection, as, for example, a pin and slot connection, with the plate member, as indicated at 77.

The motors 56 and 23 are supplied with energy from a transformer 80 having a primary winding 81 and a secondary winding 82. The bridge circuit 40 is supplied with energy by a battery 83 connected to the input terminals 41 and 42.

Operation

With the parts in the position shown in the drawing, the system has been set to maintain the space temperature at 70°, and the space temperature is at that value, as indicated by the fact that the switch arm 62 is engaging neither of the contacts 63 and 64. The operation of the system will first be considered as though the switch arm 62, and the rheostat 54 operated thereby, were omitted. If the temperature of the space being heated now falls below 70° the resistance of the element 52 is decreased. This decrease in the resistance of element 52 decreases the resistance between the terminals 41 and 43 below that between the terminals 41 and 44 of the bridge circuit. This results in an increase of the potential of terminal 43 with respect to that of terminal 44, and a current flows from terminal 43 through a conductor 85, movable coil 33 of galvanometer 34, and a conductor 84 to output terminal 44. The passage of this current through the movable coil 33 causes a deflection of the coil such as to move switch arm 30 into engagement with contact 31. This completes an energizing circuit for winding 25 of motor 23. This circuit may be traced from the left hand end of transformer secondary winding 82 through a conductor 86, a conductor 87, switch arm 30, contact 31, a conductor 88, winding 25, a conductor 89, to the right hand end of transformer secondary winding 82. Energization of winding 25 causes motor 23 to be driven in such a direction as to open the valve 13 wider and move the sliding contact 51 upward along the resistance 50 so as to decrease the resistance between terminals 41 and 44 of the bridge circuit 40.

As soon as the resistance between terminals 41 and 44 of the bridge has been decreased by an amount corresponding to the decrease in resistance of the temperature responsive resistance 52, the output terminals 43 and 44 come to the same potential, and current ceases to flow through galvanometer coil 33. The switch arm 30 thereupon moves away from the contact 31 to its neutral position and the motor 23 stops.

If the temperature in the space being heated increases, the resistance of the element 52 would increase with the result that a current would flow from terminal 44 to terminal 43 of the bridge circuit, thus passing through coil 33 in an opposite direction to that previously described. This current flowing through the coil 33 causes the switch arm 30 to be operated against the stationary contact 32. This completes an energizing circuit for the secondary winding 26 of motor 23 which may be traced from the left hand end of secondary winding 82 through conductors 86 and 87, switch arm 30, contact 32, a conductor 90, winding 26 and conductor 89 to the right hand end of secondary winding 82.

Energization of winding 26 causes operation of the motor 23 in such a direction as to drive the valve 13 towards closed position and to move the sliding contact 51 downward along the resistor 50 so as to increase the resistance between terminals 41 and 44. When this resistance has increased sufficiently to balance the increase in resistance of element 52, the current ceases to flow through coil 33, and the motor stops.

The motor 56 and the energizing circuit therefore controlled by the switch arm 62 constitute a means for compensating the control system for the amount of load thereon, the operation of which will now be discussed. When the temperature in the space being heated falls below

the desired value, the bimetal element 65 moves the switch arm 62 against contact 63. This completes an energizing circuit for winding 60 of motor 56 which may be traced from the left hand end of secondary winding 82 through conductor 88, plate member 66, bimetal element 65, switch arm 62, contact 63, a conductor 91, winding 60, and a conductor 92, to the right hand end of secondary winding 82.

10 Energization of winding 60 causes the motor 56 to drive the sliding contact arm 55 over the rheostat 54 in such a direction as to decrease the amount of resistance included in the bridge circuit. The motor 56 and the gear train 57 are 15 designed to move the switch arm 55 very slowly, for example, one degree in thirty minutes. Since switch arm 62 remains in engagement with contact 63 as long as the temperature of the space stays below the value which the system is set to 20 maintain, it will be seen that the motor 56 continues to slowly reset the position of slider 55 along resistance 54.

The object of this control system is to operate the valve 13 to a position such that the heat input from the radiator 15 to the space being heated is the same as the heat which is being lost from the space. If the space temperature decreases, it is indicative of the fact that heat is being lost from the space at a greater rate than it is being supplied to the space by the radiator 15. The purpose of the load compensating mechanism including the motor 56 and the rheostat 54 is to introduce into the bridge circuit a resistance which will cause a permanent resetting of the position of valve 13 at which the bridge circuit 40 is balanced. The amount by which the valve is reset will be proportional to the direction and duration of a deviation of the space temperature from its desired value. The effect of such a resetting on the valve 13 is to change the heat input to the space heated by the radiator 15 by an amount sufficient to make up for the increased heat loss which is causing the decrease in temperature.

If the temperature should now return to its desired value, which has been indicated as 70°, the contact arm 62 would be moved away from contact 63 by the action of the bimetallic element 65, thereby deenergizing the winding 60 of the motor 56 and terminating the resetting effect of the motor 56 on the contact arm 55. The rise in temperature would, at the same time, increase the resistance of element 52, thereby unbalancing the bridge circuit 40, so as to cause motor 23 to drive the valve 13 to a closed position. When the valve stem 20 is moved downwardly far enough to rebalance the bridge circuit through the action of sliding contact 51 on the resistance wire 50, the bridge will be rebalanced. The final valve position will differ from the original valve position by an amount proportional to the movement of slider 55 along resistance 54.

The function of the load compensating mechanism is to reset the valve position to a value such that the heat input by the radiator 15 exactly equals the heat lost from the space. The function of the temperature responsive element 52, on the other hand, is to change the valve setting temporarily by a sufficient amount to cause the heat input to be changed sufficiently to return the space temperature rapidly to its desired value. 70 As the return of the space temperature to the desired value is accomplished, the effect due to the temperature responsive element 52 is to move the valve in the opposite direction, back towards its original position. The operation of the motor 56 in driving the switch arm 55 over the resist-

ance 54, however, has caused a change in the resistance of the bridge net work which is not removed by the return of the space temperature to its original position. The valve 13 therefore stops at a different position than it was before the temperature decrease took place. The space temperature is again at 70° but the heat input to the furnace 10 and hence the heat input to the space through the radiator 15 has been increased by an amount sufficient to take care of the increased heat loss which caused the original decrease in temperature.

When the temperature of the space increases above the desired value, the operation of the load compensating mechanism is similar to that previously discussed. In this case the increase in temperature will cause the bimetallic element 65 to move contact arm 62 against stationary contact 64. This completes a circuit which may be traced from the left hand end of secondary winding 82 through conductor 86, plate member 66, bimetallic element 65, switch arm 62, contact 64, conductor 93, motor winding 61, conductor 92 to the right hand end of secondary winding 82. This circuit energizes the motor winding 61 and causes the motor 56 to be driven in such a direction as to move contact arm 55 upwardly along resistance 54, so as to increase the resistance in series with the temperature responsive element 52. This will cause a permanent resetting of the valve towards closed position, exactly similar to the resetting towards open position mentioned above.

Means have been provided for adjusting the value of the space temperature which the system is to maintain. This means comprises the extension 12 on the lever arm 70 which may be moved along the scale 74 to any desired temperature reading on the scale. While the lever 70 is shown as manually movable, it will be readily understood by those skilled in the art that a clock or other conventional automatic means might be used.

Suppose now that the lever arm 70 has been moved to the left so that the indicator 73 is opposite the figure 60 on the scale 74. This movement of the lever arm 70 will simultaneously move the contact arm 75 over the rheostat 53 so as to increase the resistance of the rheostat 53 which is in series with the temperature responsive element 52. This will cause a permanent resetting of the position of valve 13 in accordance with the new resistance value between the terminals 41 and 43 in the same manner as the increase in resistance 54 caused a permanent resetting of the valve 13 towards closed position. This will decrease the supply of fuel to the burner 11 and will therefore decrease the heat supply to the space by the radiator 15.

The temperature of the space will not of course fall at once to the new desired value, but will slowly drop. This decrease in temperature results in a decrease in resistance of element 52, and hence in an unbalance of the bridge circuit such as to cause movement of the valve towards open position. This action is however balanced to some extent by the load compensating mechanism.

When the lever 70 is moved to set the system temperature at 60°, the plate member 66 is moved by the action of the pin and slot connection 71 so that the temperature at which the switch arm 62 engages neither of the contacts 63 and 64 is changed to 60°. The temperature at the time of this change in setting being 70°, the switch arm

62 is moved against the right hand contact 64, thereby energizing the motor winding 61 through the circuit previously described. The motor 56 therefore drives the contact arm 55 in a direction to increase the portion of resistance 54 in the bridge circuit and therefore compensates to some extent for the decrease in resistance of temperature responsive element 52. When the new system temperature is reached the valve 13 remains set at its new position to which it was moved through the action of the rheostat 53.

If the rheostat 53 were not used, the only way of changing the system temperature would be to change the setting of the bimetallic element 65, and then wait for the slow operation of the load compensating motor 56 to drive the contact arm 55 over the resistance 54 by an amount sufficient to change the temperature setting of the system to its new desired value. Because of the extremely slow operation of the load compensating motor 56 the adjustment of the system temperature obtained by such a method would be unwieldy and impractical. The resistance 53 therefore provides a quick method of adjusting the system temperature.

Other modifications of our invention will readily occur to those skilled in the art. For instance, other types of bridge circuits might be readily used, or means for amplifying the output of the bridge circuit might be used. Such an amplifier might either be of the electronic type or of the type which intermittently clamps the galvanometer pointer and then operates a mechanism so that one of two or more switches is selectively closed, depending upon the pointer position. Our invention is not therefore limited to the simple embodiment disclosed herein but is defined by the appended claims.

We claim as our invention:

1. In combination, a device to be positioned in a plurality of positions for controlling the value of a condition, a bridge circuit including an element whose resistivity varies in accordance with said condition, means responsive to the unbalance of said bridge circuit for positioning said device and rebalancing said bridge, a first adjustable impedance in said bridge circuit for changing the value of said condition maintained by the device, an adjustable compensating impedance connected in said bridge circuit, means responsive to the deviation of said condition from a predetermined value for adjusting said compensating impedance, and means for simultaneously adjusting said first impedance and said deviation responsive means.

2. In combination, a device to be positioned in a plurality of positions for controlling the value of a condition, a bridge circuit including an element whose resistivity varies in accordance with said condition, means responsive to the unbalance of said bridge circuit for positioning said device and rebalancing said bridge, a first adjustable impedance in said bridge circuit for changing the value of said condition maintained by the device, an adjustable compensating impedance connected in said bridge circuit, means responsive to a condition indicative of the load on said device for adjusting said compensating impedance, and means for simultaneously adjusting said first impedance and said condition responsive means.

3. A system for maintaining a condition at a predetermined value, comprising in combination, a device to be positioned in a plurality of positions for controlling the value of a condition, an

electric circuit including a first resistance, whose resistivity varies in accordance with said condition, means responsive to the flow of current in said circuit for positioning said device, a second resistance adjustable in magnitude and connected in series with said first resistance, a third resistance adjustable in magnitude and connected in series with said first resistance, means responsive to a deviation of said condition from its predetermined value for adjusting said second resistance, manually operable means for adjusting said third resistance and thereby changing the magnitude of said predetermined value, and an operative connection between said manually operable means and said deviation responsive means whereby said deviation responsive means is adjusted simultaneously with said third resistance so as to operate upon a deviation of the condition from the value determined by said third resistance.

4. A system for controlling the temperature of a space, comprising in combination, temperature changing means, a device to be positioned in a plurality of positions for controlling said temperature changing means, a bridge circuit including a resistance element with an appreciable temperature coefficient of resistance, an adjustable resistance element connected in said bridge circuit, means including a thermostat responsive to a deviation of said space temperature from a predetermined value for adjusting said last mentioned resistance, a second adjustable resistance element connected in said bridge circuit, means for adjusting said second resistance and simultaneously changing the setting of said thermostat, and means responsive to the unbalance of said bridge circuit for changing the position of said device.

5. A system for controlling the temperature of a space, comprising in combination, temperature changing means, a device to be positioned in a plurality of positions for controlling said temperature changing means, a bridge circuit including a resistance element with an appreciable temperature coefficient of resistance, an adjustable resistance element connected in said bridge circuit, a reversible electric motor, double-throw switch means controlling the energization and rotational direction of said motor, adjustable thermostatic means responsive to a deviation of said space temperature from a predetermined value for operating said switch means, means driven by said motor for adjusting said last mentioned resistance, a second adjustable resistance element connected in said bridge circuit, means for simultaneously adjusting said second resistance element and said thermostat, and means re-

sponsive to the unbalance of said bridge circuit for changing the position of said device.

6. In combination, a device to be positioned in a plurality of positions for controlling the value of a condition, a bridge circuit including an element whose resistivity varies in accordance with a condition indicative of the need for operation of said device, means responsive to the unbalance of said circuit for positioning said device and rebalancing said circuit, a first adjustable impedance in said circuit for changing the value of said controlled condition, an adjustable compensating impedance connected in said circuit, means responsive to the deviation of said controlled condition from a predetermined value for adjusting said compensating impedance, and means for simultaneously adjusting said first adjustable impedance and said deviation responsive means.

7. In combination, a device to be positioned in a plurality of positions for controlling the value of a condition, a normally balanced electrical circuit including impedance means variable in response to a condition indicative of the need for operation of said device, means responsive to the unbalance of said circuit for positioning said device and rebalancing said circuit, a first adjustable impedance in said circuit for changing the value of said controlled condition, an adjustable compensating impedance connected in said circuit, means responsive to the deviation of said controlled condition from a predetermined value for adjusting said compensating impedance, and means for simultaneously adjusting said first adjustable impedance and said deviation responsive means.

8. In combination, a device to be positioned in a plurality of positions for controlling the value of a condition, means for modulately positioning said device, normally balanced control means for said positioning means, means responsive to changes in a condition indicative of the need for operation of said device for producing an unbalancing effect in said control means, means operated by said positioning means for opposing said unbalancing effect and rebalancing said control means, first means for varying the relationship between said unbalancing and rebalancing effects in response to deviations of said controlled condition from a predetermined value, second means for varying said relationship manually, and means associated with said second means and operated simultaneously therewith to change said predetermined value by an amount corresponding to the change in said relationship.

WILLIS H. GILLE.
